Primary Examiner — Clare E Heflin(74) *Attorney, Agent, or Firm* — JCIP Global Inc.(57) **CLAIM**

The ornamental design for a flagstaff light, as shown and described.

DESCRIPTION

FIG. 1 is a bottom perspective view of a flagstaff light showing my new design;

FIG. 2 is a top perspective view thereof;

FIG. 3 is a bottom plan view thereof;

FIG. 4 is a top plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken line portions of the flagstaff light in FIGS. 1-8 represent unclaimed portions of the claimed design and form no part thereof.
